Primary Examiner—Donald B. Moyer

Attorney, Agent, or Firm—John H. Calhoun, Jr.

[57] CLAIM

The ornamental design for a wig rain cap, as shown and described.

DESCRIPTION

FIG. 1 is a front elevational view of a wig rain cap showing my new design;

FIG. 2 is a right side elevational view, the left side view being a mirror image thereof; and

FIG. 3 is a rear elevational view thereof.

FIG 1.

FIG 2.

FIG 3.
